UNITED STATES PATENT OFFICE.

JOHN HENRY WALKER, OF LEXINGTON, KENTUCKY.

TROLLEY-POLE CATCHER.

No. 852,307.

Specification of Letters Patent.

Patented April 30, 1907.

Application filed June 27, 1906. Serial No. 323,622.

To all whom it may concern:

Be it known that I, JOHN HENRY WALKER, a citizen of the United States, and a resident of Lexington, in the county of Fayette and State of Kentucky, have invented certain new and useful Improvements in Trolley-Pole Catchers, of which the following is a specification.

This invention is an improvement in trolley pole catchers, and particularly in that class of such devices illustrated by my former patent No. 787,810, issued April 18, 1905; and the present invention relates to certain improvements in the track rail and in the carrier operating thereon; and the invention consists in certain novel constructions and combinations of parts as will be herein-after described and claimed.

In the drawings Figure 1 is a side elevation partly in section of an apparatus embodying my invention in which the dog of the carrier is adjusted clear of the rack so the carrier may slide freely back and forth along the track. Fig. 2 is a detail side view, the cover being removed, of a portion of the track with the carrier in place and with the dog and the supplemental catch adjusted into engagement with the rack to lock the carrier from movement toward the trolley stand. Fig. 3 is a view similar to Fig. 2, with the carrier adjusted back to the position in which the supplemental catch engages in the safety notch at the outer end of the track. Fig. 4 is a vertical longitudinal section of the carrier, the cover being removed. Fig. 5 is a cross-section on about line 5—5 of Fig. 4. Fig. 6 is a horizontal section drawn through the carrier cover above the supplemental catch, and Fig. 7 is a transverse section of the cover on about line 7—7 of Fig. 6.

In the present construction the carrier comprises a body A, a rocker B, and when desired, a cover C for protecting the body and rocker and attached parts from the weather, dust and the like. The body A is slotted longitudinally at A' forming a passage for the track D so the carrier may slide back and forth along the track. The slot is formed in the bottom of the body A and the top wall A' of the slot rests upon the upper edge of the track D, while a strip E dovetailed in the body A at the base of the slot A' forms a bearing to slide along the lower edge of the track D, as will be understood from Figs. 1, 4 and 5 of the drawings. An opening A² leads through the top of the body A into

the slot A' and affords a passage for the wick extending from the waste F which is suitably oiled and is held within a box G fitted in a suitable recess in the top of the body A, and is provided with a spout g through which the waste in the form of a wick passes, as shown in Fig. 4, and the box G has springs G' by which it is steadied in place when inserted, as shown in Fig. 6. This construction operates to lubricate the track and facilitates the sliding of the carrier thereon.

The body A is provided on its upper side with an upwardly projecting block or portion A³ through which passes the bolt A⁴ forming a pivot on which the rocker B tilts in adjusting the said rocker to and from the position in which it sets the dog into engagement with the track and into and out of position for freeing the supplemental catch presently described from engagement with the rack. This portion A³ also forms a guide through which is passed a rod H which is movable longitudinally is actuated in such direction by a spring H', and is provided with a stud H² preferably in the form of a threaded bolt so it may be adjusted as desired, and which engages with a bearing H³ in the form of a pin or bolt on the rocker B, the purpose of such construction being to hold the rocker B yieldingly when adjusted to either of the positions shown in Figs. 2 and 4 of the drawings. Thus, when the rocker is adjusted to the position shown in Fig. 2 the stud H² engaging below the bearing H³ will prevent the accidental shifting of the rocker to the position shown in Fig. 4, while when the rocker is in the position shown in Fig. 4 it will be held by the stud from accidental shifting as shown in Fig. 2. If, however, when the parts are in the position shown in Fig. 4, the trolley pole slips from the wire, the bearing H³ will be actuated by the force of upward movement of the trolley pole past the stud H² to the position shown in Fig. 2, and the dog will engage with the rack on the lower edge of the track bar, and if the trolley pole be pulled down suddenly the action will force the rocker back to the position shown in Fig. 4, in which the bearing H³ will engage beneath the point of the stud. The spring actuated rod H with its stud or point H² thus operates as a means for holding the dog presently described, in engagement with the track, and also as a means for holding the dog out of such engagement, according to the adjustments of the rocker.

- The dog I is carried at the lower front end of the rocker B, and the supplemental catch J is carried at the upper rear end of the body A, and means are provided whereby the rocker when adjusted to position to free the dog from engagement with the rack will also hold the supplemental catch out of engagement with the track, this being shown in Fig. 1, and being more fully described hereinafter.
- 10 The track D is provided in its lower edge with a series of notches D', and in its upper edge with a series of notches D², and at the rear end thereof with a safety notch d'. The lower notches D' are to receive the point of the dog I, which dog is pivoted between its ends at I' to the rocker B at the lower front end of said rocker, the dog having a rearwardly projecting tail-piece I², which operates by engagement with the points of the
- 15 teeth formed by the notches D' to throw the point I² of the dog positively into engagement with the teeth formed at the lower edge of the rack as will be understood from Figs. 2 and 3 of the drawings, a cross-pin i², see Figs.
- 20 1 and 4, limiting the upward movement of the tail-piece of the dog and holding the said part so it will engage with the points of the teeth on the track D, and throw the point of the dog into engagement with the teeth when
- 25 the parts are adjusted to the position shown in Fig. 2. At the same time when the rocker is in the position shown in Fig. 4, the tail piece will be held out of engagement with the rack teeth, as will be understood from said
- 30 Fig. 4.
- The supplemental catch J is pivoted at J' to the upper rear end of the body A, and may drop by gravity into engagement with the notches D' and d' when free to do so, but I
- 35 prefer to provide a spring J² to aid in actuating the supplemental catch to secure a prompt operation thereof when the dog is released, and permit it to lower to the position shown in Fig. 2 or to the position shown in Fig. 3,
- 40 according to the location of the carrier upon the track. When the rocker is in the position shown in Figs. 1 and 4, the catch J is held out of engagement with the track by means of one or more pins J³ which are mov-
- 45 able vertically in the body A, engaging at their upper ends below the catch J, and are in position at their lower ends for engagement by the rear end of the rocker B, so said rocker when tilted to the position shown in Figs. 1
- 50 and 4 will lift the catch J, and hold it out of engagement with the track. Thus the rocker operates when in position to hold its dog clear of the track to lift the catch so it will not impede the free movement of the carrier
- 55 back and forth along the track. At the same time, however, when the dog is adjusted into engagement with the track the rocker moves out of engagement with the pins J³ and the supplemental catch is dropped into engage-
- 60 ment with the top rack forming a safety

catch and supplementing the dog in preventing the carrier from sliding toward the trolley stand and permitting the trolley pole to swing to an upright position, when the trolley escapes from the wire.

The trolley L is mounted on a stand L' from which the track D extends as shown, and this trolley is connected by a rod or rods L² with the front end of the rocker, and the connection is preferably a slidable one effected by slotting the rod or rods L to receive the bolt L³ connecting it with the dog so the trolley pole when moving either down or up will gain some speed of movement before it operates the rocker so that the rods L² will operate upon the rocker with a hammer stroke which will aid in adjusting the bearing H² of the rocker out of engagement with the stud.

It is in some instances desirable to move the trolley pole down flat upon the top of a car, in which case it is ordinarily tied down but the supplemental catch operating in the safety notch D' may be utilized to hold the trolley pole in its lowered position. In such operation it becomes necessary to tilt the rocker downwardly at its rear end to relieve the safety catch, and this is effected by means of a tongue or extension b at the rear end of the rocker moving into engagement with a pivoted cam M at the rear end of the track D. This cam M has an inclined edge M' which when engaged by the extension b will force said extension down thus moving the rocker out of engagement with the pins J³ and permitting the supplemental catch to drop into the safety notch d', as shown in Fig. 3. The plate M is pivoted at M² in such manner that it is rigid as against rearward movement from the position shown in Fig. 3, but when it is desired to release the trolley pole after it has been lowered, a slight further downward movement of the trolley pole will force the tongue b in rear of the cam M, and said cam will rock when the carrier is moved forward to the position indicated in dotted lines in Fig. 3, and the carrier may be moved freely forward, the pressure of the rod L² on the front end of the rocker tilting the rocker down at its front end so its dog I will be clear of the rack and the rear end of the rocker will lift the supplemental catch so it will ride free of the notches in the upper end of the track, as will be understood from the drawing.

It may be desirable to incase the carrier, and I prefer to do this by means of the cover C in the form of a case fitting over the carrier and slotted in its front edge at C' and in its rear edge at C² for the passage of the track D, and provided with the upright ribs C³ near its rear end to fit alongside the rear edge of the body portion of the carrier, the cover being extended at C⁴ in rear of the rib C³ to properly house the supplemental catch, as

will be understood from Figs. 1 and 6 of the drawings.

In operation when the parts are in the position shown in Fig. 1 the trolley pole may be held down or permitted to rise without interference with the carrier, the latter sliding freely along the track. If, however, the trolley pole should escape from its wire the initial upward movement of the trolley pole will cause the rocker to tilt from the position shown in Fig. 1 to that shown in Fig. 2, the slotted construction of the trolley pole facilitating such operation by the hammer action above described. This will throw the dog up and permit the supplemental catch J to engage with the track and prevent the upward movement of the trolley pole. Then when it is desired to re-apply the trolley pole to the wire, the sudden downward movement of the trolley pole will readjust the rocker to the position shown in Fig. 1, setting the dog out of engagement with the track and lifting the supplemental catch from said engagement and the trolley pole may be manipulated as desired.

I claim—

1. The combination substantially as described, of a track having its upper and lower edges notched, the trolley pole, the carrier having a body portion sliding along the track and provided above the track with a supplemental catch for coöperating with the top notches, a pin or pins extending through the body portion and engaging with the supplemental catch, and a rocker pivoted to the body portion and extending below the position to operate said pin or pins, a spring actuated rod extending longitudinally above the track and having a stud, a bearing on the rocker for engagement by said stud, a dog pivoted between its ends to the rocker and having its front end or point arranged to co-operate with the notches in the lower edge of the track and its rear portion or tail piece to engage with the track and adjust the said front end or point into locking engagement with the track, a tongue at the rear end of the rocker, and a cam pivoted to the track for engagement by said tongue.
2. The combination with a trolley pole and a track, of a carrier sliding thereon and having a body portion and a rocker pivoted thereto and provided with a dog for engagement with the track, and a rod extending between the rocker and the trolley pole and having a sliding connection with the one of said parts whereby it may operate with a hammer action.
3. The combination with a trolley pole and a track, of a carrier sliding on the track and having a body portion and a rocker pivoted thereto, connections between the rocker and trolley pole, a dog on the rocker for engagement with the track, a supplemental catch on the body portion for engagement

with the track, and means for freeing the supplemental catch from engagement with the track.

4. In an apparatus substantially as described, a carrier comprising a body portion, a rocker, a dog carried by the rocker, a supplemental catch carried by the body portion, and means whereby the rocker when adjusted to position to free the dog may also adjust the supplemental catch to neutral position.

5. The combination with the track, of a carrier sliding thereon and having a body portion and a rocker pivoted thereto, a dog carried by the rocker and movable therewith into and out of position to engage the track, a catch carried by the body portion, and means whereby the rocker may adjust the supplemental catch to neutral position when the dog is moved out of engagement with the track.

6. In a trolley pole catcher, the combination with a track having a safety notch, of a carrier movable on the track and having a body portion provided with a supplemental catch to enter the safety notch, and a rocker pivoted to the body portion and having a rearwardly projecting tongue, means whereby the rocker when raised at its rear end may move the supplemental catch out of the safety notch, and means at the rear end of the track for operating upon the tongue of the rocker to depress the rear end of the rocker.

7. The combination with a track, of a carrier movable thereon and having a body portion provided with a supplemental catch and a rocker provided with a dog, intermediate devices between the rocker and supplemental catch whereby the rocker may adjust the latter to neutral position, and a cam plate pivoted to the track in position for engagement by the rear end of the rocker whereby to depress the same, the cam plate being pivoted to swing freely in a direction toward the carrier.

8. The combination in a trolley pole catcher of a track having a rack at its upper edge and a rack at its lower edge, the carrier sliding along the track and having a body portion and a rocker pivoted thereto, a dog pivoted to the rocker for engagement with the lower rack of the track, and a catch pivoted to the body portion for engagement with the top rack of the track.

9. The combination of a trolley pole, a track extending longitudinally therefrom, a carrier sliding along the track and having a body portion and a rocker pivoted thereto and provided with means for engagement with the track to lock the trolley against upward movement on its sudden escape from the wire, and a supplemental catch on the body portion for engagement with the track.

10. The combination in a trolley pole catcher of a carrier having a body portion, a

- rocker pivoted thereto and provided with a dog and a supplemental catch pivoted to the body portion and having a portion projecting in rear thereof and a cover fitting over the carrier and having its opposite ends slotted for the passage of a track bar, and provided on its inner side with upright ribs fitting along the rear edge of the body portion of the carrier and with a portion extending beyond said ribs forming a housing for the supplemental catch.
11. The combination in a trolley pole catcher with the body portion of a sliding carrier, of a rocker pivoted between its front and rear ends thereto, a dog at the front end of the rocker, a supplemental catch at the upper rear end of the body portion, and a pin extending through the body portion and arranged at its upper end to engage beneath the supplemental catch to lift the same and extending at its lower end into position to be operated by the rear end of the rocker.
12. The combination of a trolley pole, a track having its lower edge notched forming teeth, a carrier movable along the track and having a dog pivoted between its ends forming a front end or point for engagement with the track and a rear end or tail piece to engage with the teeth of the track for throwing the point end into engagement therewith, and means whereby the initial upward move-

ment of the trolley pole on escapement from the wire will throw the dog into engagement with the track to lock the trolley pole against further upward movement.

35

13. The combination in a carrier for trolley pole catchers of the body portion having a longitudinal passage for a track bar, and a rod movable longitudinally in the body portion above said passage and provided at one end with a presser point, a spring actuating said rod longitudinally, and a rocker having a dog for engagement with the track bar, said rocker being pivoted to the top portion and provided with a bearing for engagement by the presser point of said spring actuated rod.

14. The combination with the trolley pole and track bar extending longitudinally therefrom, of a carrier sliding on the track bar and connected with the trolley pole for operation thereby, a catch on the carrier for engagement with the track bar when the trolley pole is pulled down to the car, means on the carrier for releasing said catch under certain conditions, and means on the track bar for restraining said catch releasing means from releasing the catch.

JOHN HENRY WALKER.
